GARBAGE DISPOSAL TRUCK

Hiram Vander Veen, Berwyn, Ill.

Application November 19, 1954, Serial No. 470,006

1 Claim. (Cl. 241—46)

This invention relates to devices for garbage disposal purposes, and more particularly has reference to a garbage collection disposal truck for collecting untreated garbage and grinding the garbage with water and flushing the ground garbage down a sewer manhole or the like.

The primary object of the invention is to provide a practical and efficient device of this kind which reduces the work and expense of municipal collection and disposal of garbage and enables a smaller number of trucks to accomplish collection and disposal of garbage in a municipality.

Another object of the invention is to provide in a device of this kind a grinding unit which is easily installed on existing garbage collection trucks, the unit being efficient and reliable in operation, being capable of easy installation, and being capable of being made in mechanically efficient and easily served forms at relatively low cost.

Other objects of the invention will appear from the following description, and from the accompanying drawings, in which like reference characters designate like parts throughout the several views, and wherein:

Figure 1 is a fragmentary side elevational view of a device in accordance with the present invention showing it in relation to a fire-plug and a sewer manhole;

Figure 2 is a top plan view of Figure 1;

Figure 3 is an enlarged vertical longitudinal sectional view taken on line 3—3 of Figure 1;

Figure 4 is a vertical transverse sectional view, on the scale of Figure 3, taken on line 4—4 of Figure 2;

Figure 5 is a transverse vertical sectional view on line 5—5 of Figure 3; and

Figure 6 is a fragmentary transverse vertical sectional view on line 6—6 of Figure 3.

Referring in detail to the drawings, a garbage collection truck 10 is illustrated in Figure 2 as having a power take off shaft 12 extending to the rear thereof and terminating in a gear box 14 from which extends a lateral shaft 16 having on its laterally outward end a drive sprocket 18 about which is trained a sprocket chain 20. The truck 10 has a back wall 11 having in the lower part thereof a discharge opening 13 normally closed by a vertically movable gate 15. The floor 17 of the truck terminates at its rear end in a rearwardly declining lip 19 forming the bottom of the discharge opening 13. A chassis cross member 21 at the rear of the truck 10 underlies the floor 17 in the region of the back wall 11, as shown in Figures 4 and 5. In accordance with the present invention, a garbage disposal device, generally designated 29, is mounted on the rear side of the truck cross member 21, beneath the garbage discharge opening 13. The device 29 comprises a horizontally elongated housing 32 having a front wall 31, a rear wall 33, a bottom wall 35, and a top wall 37. The top wall 37 has therein an elongated opening 39' into which the declining lip 19 extends.

Within the housing 32 are first and second vertical partition walls 39 and 41 which define therebetween a grind-

2

ing chamber 43, and the partition walls are inwardly spaced from related ends of the housing, which have thereon inwardly projecting flanges 45 and 47, respectively. Vertical end plates 49 and 51 are secured to the flanges 45 and 47 and close the ends of the housing 32.

In the upper part of the grinding chamber 43 is a pair of meshed helical grinding rolls 44 and 46 which are journaled at one end in the partition wall 41, as indicated at 49'. The rolls reach to the partition wall 39 and have shafts 40 extending therethrough in bearings 51 on the wall 39. In the space between the partition wall 39 and the end plate 49, serving as a gear case, one of the shafts 40 has thereon a gear 36 which is in mesh with a pinion 34 on a shaft 24 which is journaled in bearing 53 on the partition wall 39 and a bearing 26 on the end plate 49. On its outer end the shaft 24 has a sprocket wheel 22 over which is trained the chain 20. The grinding rolls 44 and 46 have threads 55 which are meshed so that the rolls rotate together.

Declining guide plates 48 and 50 on the upper ends of the housing front and rear walls 31 and 33 have free edges closely spaced from adjacent sides of the tops of the rolls 44 and 46, as shown in Figure 4, whereby garbage emerging from the truck discharge opening 13 is guided onto the rolls.

Centered beneath the rolls 44 and 46 is a screw conveyor 66, having a stub shaft 42 on one end journaled through the partition wall 39 in a bearing 57 and having thereon a gear 38 in mesh with the pinion 34. On the other end of the conveyor is a stub shaft 59 which is journaled through a foraminous plate 70 secured to the outer side of the partition wall 41 across an opening 68 in this wall, whereby garbage ground by the rolls 44 and 46 is conveyed by the conveyor 66 and forced through the foraminous plate 70 into the discharge chamber 61 defined between the partition wall 41 and the housing end plate 51. A nozzle 76 depends from the housing bottom wall at the discharge chamber 61, and a flexible hose 78 has one end secured around the nozzle 76 and a free end 77 adapted to be positioned in a sewer manhole S.

The housing bottom wall 35 is interrupted between the partition walls 39 and 41 and therat takes the form of a V-shaped trough 67, as shown in Figure 4, with the conveyor 66 occupying the apex portion 79 thereof.

Secured at its ends upon the top wall 37 of the housing 32, as indicated at 79, and extending forwardly partly across the opening 39' in the housing top wall 37 which extends between the partition walls 39 and 41, is a water spray nozzle 56 which includes a perforated flat bottom wall 60 and an imperforate top wall 83, with a central fitting 62 on the rear thereof, to which is connected one end of a water hose 64 whose other end is adapted to be connected to a fire hydrant H or other source of water under pressure.

When the power take-off 12 is in operation and the gate 15 open and garbage falling through the truck back wall opening 13 into the opening 39' of the housing 32, with water being sprayed by the nozzle 56, the garbage will be ground by the rolls 44 and 46 and pass downwardly therebetween and be forced, together with entrained water, through the foraminous plate 70, into the discharge chamber 61, and discharged through the hose 78 into the sewer opening S.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles, it being considered that the invention comprehends any minor change in construction.

tion that may be permitted within the scope of the appended claim.

What is claimed is:

In the garbage disposal unit, a horizontally elongated housing having top, bottom, and front and rear walls and ends, first and second vertical partition walls in said housing extending between said walls and spaced inwardly from said ends, said partition walls defining a grinding chamber therebetween and said top wall having an intake opening extending between said partition walls, a pair of meshed threaded grinding rolls in the upper part of said grinding chamber, said rolls having one end journaled in said second partition walls and stub shafts journaled through said first partition wall, end plates secured to and closing the ends of the housing and defining a gear case with said first partition wall and a discharge chamber with said second partition wall, one of the grinding roll shafts having a gear thereon in said gear case, a drive shaft journaled through the end plate of the gear case and having a pinion in the gear case meshed with the roll shaft pinion, said housing bottom wall being interrupted between said first and second partition walls and formed into a V-shaped trough having an apex, a screw conveyor positioned in the apex of the trough and having a first stub shaft journaled through said first partition wall
